UNITED STATES PATENT OFFICE.

CHARLES T. COE, OF KEARNEY, NEW JERSEY.

SECTIONAL SHAKING AND DUMPING GRATE.

1,098,228.

Specification of Letters Patent. Patented May 26, 1914.

Application filed October 1, 1912. Serial No. 723,239.

To all whom it may concern:

Be it known that I, CHARLES T. COE, a citizen of the United States, and a resident of Kearney, in the county of Hudson and State of New Jersey, have invented certain new and useful Improvements in Sectional Shaking and Dumping Grates, of which the following is a specification.

This invention relates to a sectional shaking and dumping grate.

It is an improvement of my invention filed January 30th, 1909, Serial Number 475,091, and is characterized by novel dumping frames with grate sections, and novel means to secure the latter in said frames to prevent their detachment when using the grate.

In the accompanying drawings, Figure 1 represents a plan view of a grate exemplifying the invention with a fragmentary portion of a furnace, Fig. 2 is a partial front view and section of Fig. 1 on the line 2, 2, Fig. 3 shows a side view of one of the intermediate side bars of the grate, Fig. 4 represents a top plan view of Fig. 3, Fig. 5 shows a fragmentary side view of an end side bar, Fig. 6 shows an enlarged fragmentary front view of a dumping frame of the invention with a section as on the line 6, 6 of Fig. 8, Fig. 7 is a top plan view of a dumping frame with its grate sections, Fig. 8 represents an end view of the dumping frame, Fig. 9 shows a partial section of Fig. 6 on the line 9, 9, Fig. 10 shows a section similar to Fig. 9 with a modification, Fig. 11 represents a top plan view of a modified dumping frame, Fig. 12 is an end elevation of Fig. 11 and Fig. 13 shows a side view of a portion of the end side bar with fragmentary portions of dumping frames.

The invention comprises a furnace having intermediate side bars 20 and end side bars 21. The bars 20 have sockets with the vertical walls 23, 24 and the cylindrical bearings 25 of greater diameter than the distance between the said walls. A lug 26 intermediate of the sides of the bar and extending from the upper face thereof forms the wall 24. The bars 20 also have sockets with the cylindrical bearings 28 of a diameter equal to the distance between the walls 29 of the latter sockets.

The bars 21 have sockets with the walls 33, 34 and the cylindrical bearings 35 of greater diameter than the distance between the latter walls. A lug 36 extends from the top and outer face of the latter bar and

forms the wall 34. The bars 21 also have the sockets with the cylindrical bearings 38 of a diameter equal to the distance between the walls 39 thereof. In the ends of the 60 said bars are formed dovetailed sockets 42 that engage lugs 43 of the cross braces 44, the latter each having corrugations shown at 45 and 46. Between the said side bars are located the dumping frames comprising 65 each the end walls 51 which are connected by the top flange 52, indented or corrugated in the edges thereof as shown at 53 and 54. The raised portions 53 of the edge of the flange of one frame interlocks with the depressions of the edge of the flange of the frame next adjacent, and at the ends of the 70 grate the raised portions 53 of the dumping frames interlock with the depressions 46 of the cross braces 44. The said flange 52 has 75 formed therewith the inclined longitudinal bearing brace 55 and the shouldered longitudinal bearing brace 56. A lower longitudinal connecting brace 57 extends between the end walls 51 and has extending therefrom the hooks 58 and the forked leg 59. The end walls 51 have each extending therefrom the cylindrical trunnions 60 with the 80 segmental portions having the flat faces 61, which latter are vertical when the dumping 85 frames are in their normal positions. The said trunnions are in this instance shown with their centers in a vertical line intersecting the ends of the flanges 52, and are supported on the bearings of the sockets in 90 the bars. Connecting braces 62, 63 extend between the flange 52 and the brace 57. Grate sections are located between the walls 51 and are supported on the bearing braces 55 and 56. Each grate section comprises 95 the bars 66 that are formed with the connecting braces 67. The bars 66 are curved at their upper edges and at their rear ends have formed therewith the heels 68, that bear and lock with the braces 56, and at their front ends they have the inclined bearing surfaces 69, that bear on the braces 55.

From each grate section extends a lug 70 with a hook 71, and a connecting link 72 connects this hook with one of the hooks 58 extending from the connecting brace 57. Pins 73 supported by the legs 59 of a number of the dumping frames are joined by the connecting bar having the upper member 75 and the lower member 76. From the latter extends a lug 77 to which is secured a reach rod 78, by means of the jam nuts 79.

From the front end of each reach rod extends a forked connection 80. To the front 85 of the furnace are pinned the links 86, and a shaking link 87 connects each link 86 with 5 the said forked connection.

In Fig. 10 the grate section is modified and from one of the bars 95 thereof, extends a lug 96 with an opening 97 for the connecting link 72. In Figs. 11 and 12 the 10 dumping frame is shown with its top flange 90 devoid of corrugations in the edges thereof.

To use the grate the operator preferably by means of a shaking bar, reciprocates one 15 of the shaking links 87, and thereby one of the sets of dumping frames is swung. To locate the trunnions of the dumping frames on their bearings, they do not require to be tilted when passing through the parallel 20 walls of the sockets.

When the dumping frames are swung as shown in the rear portion of the furnace and particularly in Figs. 1, 2 and 13, the 25 ends of the trunnions 60 extend beyond the vertical walls 24 and 34 of the sockets in the intermediate side bars 20 and end bars 21, thereby locking said trunnions and consequently their dumping frames with said side bars. This avoids the necessity of 30 tilting the dumping frames when they are put in place. Some of the bearings like 28 and 38 in the said bars have their walls separated a distance equal to the diameters of 35 their bearings, to show that the special dumping frames can be used with such bearings.

The trunnions 60 being formed with their full cylindrical bodies adjacent to the walls 51 of the dumping frames and only segmented at their ends, form strong and novel 40 structures not easily broken by rough handling.

The coaction of the interlocking flanges of the dumping frames, as well as the 45 interlocking of the flanges of the end dumping frames with the corrugated cross braces 44, provides means to cut any caked fuel that may be formed upon the grate, and also allows the frames to be close 50 enough together to be enabled to use very fine fuel.

It will be noted that the dumping frames have no cross walls between the end walls 51, that two of the grate sections abut with 55 their outer end walls against the walls 51 of the dumping frames, and that the other ends of the outer grate sections abut against

the inner grate section in each dumping frame.

Having described my invention what I 60 desire to secure by Letters Patent and claim is:

1. In a grate frame comprising upper longitudinal bearing braces, end walls connecting said braces, a lower connecting brace 65 connecting said end walls, a leg extending from the lower brace, grate sections supported upon said upper braces, the outer ends of a pair of said grate sections abutting against the end walls of the grate 70 frame, and the other ends of the pair of grate sections abutting against the end face of an accompanying grate section.

2. A grate frame comprising an inclined bearing brace and a shouldered bearing 75 brace at the upper portion thereof, the said braces having corrugated edges, end walls connecting said braces, grate sections supported on said braces, a lower connecting brace connecting the end walls, and a leg 80 extending from the lower brace.

3. A grate frame comprising bearing braces at the upper portion thereof, end walls connecting the braces, a lower connecting brace between the end walls, hooks 85 formed on the lower brace, grate sections supported on said braces of the upper portion of the frame, a hook formed on each grate section and a link connecting the hook of each grate section with one of the hooks 90 of said lower connecting brace.

4. For a grate the combination of supporting bars having bearings formed therein, cross braces locked with the bars, dumping frames having trunnions extending 95 from the sides thereof and the latter supported on the bearings of said supporting bars, each dumping frame having a lower connecting brace with a plurality of hooks extending therefrom, grate sections each 100 having a hook extending therefrom supported on each dumping frame, a link connecting the hook of each grate section with a hook on said lower connecting brace of its dumping frame and means to swing said 105 dumping frames with their grate sections.

Signed at the borough of Manhattan in the county of New York and State of New York this 24th day of September A. D. 1912.

CHARLES T. COE.
